AUTOMATIC FAN ATTACHMENT FOR
SEWING MACHINES

Paul Parkoff, Brooklyn, N. Y.

Application December 16, 1937, Serial No. 180,098

9 Claims. (Cl. 170—173)

This invention relates to new and useful improvements in an automatic fan attachment for sewing machines.

The invention has for an object the construction of an attachment as mentioned which is characterized by a pair of opposed semi-cylindrical members for engagement on a shaft, for driving the sewing machines, and flexible blades mounted on said members, substantially radially 10 of said shaft and adapted to act to circulate the air about, as the shaft turns.

The invention is particularly intended for gangs of sewing machines in shops. Under the pressure of mass production, the workers become heated, 15 particularly in the summertime, and the circulation of air is desirable.

Still further the invention proposes the provision of foundation strips mounted upon the semi-cylindrical members, and said flexible fan blades 20 being adapted to be mounted on said foundation strips.

Still further the invention contemplates an arrangement whereby the foundation strips may be adjusted to various positions so that the characteristics of the air circulation may be controlled. The arrangement permits a greater or lesser draft to be set up and permits the draft to be directed in various directions. This is particularly desirable where certain workers are more 30 sensitive to drafts than others.

For further comprehension of the invention, and of the objects and advantages thereof, reference will be had to the following description and accompanying drawings, and to the appended 35 claims in which the various novel features of the invention are more particularly set forth.

In the accompanying drawing forming a material part of this disclosure:—

Fig. 1 is a plan view of a gang of sewing machines and fan attachments according to this invention applied thereto.

Fig. 2 is an end elevational view of Fig. 1.

Fig. 3 is a fragmentary perspective view showing the fan attachment per se.

Fig. 4 is a fragmentary sectional view taken on the line 4—4 of Fig. 3.

Fig. 5 is a perspective view of a fan attachment constructed according to a modification of this invention.

Fig. 6 is a sectional view taken on the line 6—6 of Fig. 5.

Fig. 7 is a plan view of Fig. 5 with some of the parts removed.

Fig. 8 is a perspective view of a fan blade constructed according to this invention.

Fig. 9 is a vertical sectional view taken on the line 9—9 of Fig. 8.

In Fig. 1 there are work benches 10 upon which sewing machines 11 are mounted. Between the work benches there is a main drive shaft 12. 5 This drive shaft is provided with pulleys 13 which are engaged by belts 14 extending upwards and serving to drive the sewing machines. The operators sit upon chairs 15 outside of the benches 10. The automatic fan attachments, according 10 to this invention, are mounted at spaced positions upon the shaft 12.

Each fan attachment comprises a pair of opposed semi-cylindrical members 16 for engaging about and on the shaft 12. A means is provided 15 for fixedly holding these members on the shaft. This means includes flanges 16^a on each of the members and adjacent each other and secured together with bolts 17. A foundation strip 18 is mounted on each member 16. A flexible fan blade 20 19 is mounted on each foundation strip 18 and projects substantially radially of the shaft 12.

Each foundation strip 18 is formed with a dove-tailed groove 20 engaged by a dove-tailed portion 19^a formed upon the inner edge of the fan blade 25 19. Preferably, the fan blade 19 is constructed of sheet rubber material so as to be flexible.

Each foundation strip 18 is formed with several longitudinal slots 21 which are engaged by screws 22 extending downwards into the material 30 of the member 16. It is possible to loosen these screws 22 and shift the foundation strip 18 longitudinally of the shaft and so change the position of the fan blades 19 relative to an operator of one of the sewing machines. 35

Fan blades 19^{''} are interposed between flanges 16^a of the semi-cylindrical members 16 and are held by the bolts 17. The details of the blades 19^{''} will be given later on in this specification. The fan blades 19 may be entirely removed from 40 dove-tailed grooves 20, if so desired.

In Fig. 5, a modification of the invention has been disclosed which distinguishes from the prior form essentially in the fact that each fan blade 19 has its outer edge of arcuate formation. Still 45 further each foundation strip 18['] is secured by the screws 22 to a base strip 16[']. Each base strip 16['] is swivelly mounted upon the member 16. The swivel construction is as follows: An inverted T-shaped groove 24 is formed in the outer 50 surface of each member 16 and is extended in from one end thereof and terminates substantially at the center of the member.

A headed peg 25 projects from the bottom of the base strip 16['] and is adapted to fit within the 55

groove 24. The outer surface of the headed peg 25 is formed with knurlings 26. A set screw 27 threadedly engages through the side of the member 16 and its inner end abuts the headed stud 25 to engage the knurlings and firmly hold the base strip 16' in a fixed position.

It is possible to loosen the set screws 27 and then to turn the base strip 16' to various angular positions, for example, the angular position 16" illustrated by the dot and dash lines in Fig. 7. The set screw 27 may then be screwed in again to hold the base strip in its new position. As the foundation strip 18' is mounted on the base strip, it will be correspondingly turned and so will the blade 19'. A change in the angle will affect the air circulating qualities of the fan.

In Figs. 8 and 9 the details of the fan blades 19" are shown. Each blade consists of a metallic or rigid core portion 30' and a soft covering portion 30. The core portion 30' has a wide base from which the side walls taper to a point. The covering portion 30 is similarly shaped and engages over the core portion. The covering portion 30 has several cut out areas 32 exposing 25 openings 33 in the core portion. The bolts 17 are adapted to engage through these openings to hold the fan blade 19" in position. Adjacent the openings 32 the covering portion 30 has finger sections 31. These finger sections are adapted to engage beneath the flanges 16' as clearly shown in Figs. 3 and 5. In Fig. 9, the dot and dash lines indicate the position of the member 16 with respect to the fan blade. Preferably, the covering portion 38 is of rubber.

It is to be understood that any number of blades may be used in this fan attachment, constructed of suitable material, preferably with soft edges, and of any desired size and shape for fastening same securely to the drive shaft.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:—

1. A fan attachment for sewing machines comprising a pair of opposed semi-cylindrical members for engagement on a shaft, means for holding said members fixedly on said shaft, foundation strips mounted on said members and flexible fan blades mounted on said strips and projecting substantially radially of said shaft, and means for adjustably holding said foundation strips, comprising slots in the foundation strips, screws engaging through said slots and threadedly engaging said members and adapted to clamp the foundation strips in fixed positions.

2. A fan attachment for sewing machines comprising a pair of opposed semi-cylindrical members for engagement on a shaft, means for holding said members fixedly on said shaft, foundation strips mounted on said members and flexible fan blades mounted on said strips and projecting substantially radially of said shaft, said foundation strips being indirectly mounted on said members and directly mounted on base strips which in turn are mounted on said members.

3. A fan attachment for sewing machines comprising a pair of opposed semi-cylindrical members for engagement on a shaft, means for holding said members fixedly on said shaft, founda-

tion strips mounted on said members and flexible fan blades mounted on said strips and projecting substantially radially of said shaft, said foundation strips being indirectly mounted on said members and directly mounted on base strips which in turn are mounted on said members, and means for turnably supporting said base strips.

4. A fan attachment for sewing machines comprising a pair of opposed semi-cylindrical members for engagement on a shaft, means for holding said members fixedly on said shaft, foundation strips mounted on said members and flexible fan blades mounted on said strips and projecting substantially radially of said shaft, said holding means comprising flanges on said members, and bolts connecting said flanges, comprising a headed stud engageable in a complementary groove in the member, and set screws for holding the studs in various turned positions.

5. A fan attachment for sewing machines comprising a pair of opposed semi-cylindrical members for engagement on a shaft, means for holding said members fixedly on said shaft, foundation strips mounted on said members and flexible fan blades mounted on said strips and projecting substantially radially of said shaft, and means for adjustably holding said foundation strips, comprising slots in the foundation strips, screws engaging through said slots and threadedly engaging said members and adapted to clamp the foundation strips in fixed positions, said fan blades comprising a blade proper and a soft covering material to pad the edges of the blade.

6. A fan attachment for sewing machines comprising a pair of opposed semi-cylindrical members for engagement on a shaft, means for holding said members fixedly on said shaft, foundation strips mounted on said members and flexible fan blades mounted on said strips and projecting substantially radially of said shaft, and means for adjustably holding said foundation strips, comprising slots in the foundation strips, screws engaging through said slots and threadedly engaging said members and adapted to clamp the foundation strips in fixed positions, said fan blades comprising a blade proper and a soft covering material to pad the edges of the blade, extensions projecting from the said covering material, adapted to be clamped by the said foundation strip on the blade proper.

7. A fan attachment for sewing machines comprising a pair of opposed semi-cylindrical members for engagement on a shaft, means for holding said members fixedly on said shaft, foundation strips mounted on said members and flexible fan blades mounted on said strips and projecting substantially radially of said shaft, each of said members having flanges opposed to each other, and bolts through said flanges for holding the members on said shaft, fan blades secured between the said flanges by the last said bolts.

8. A fan attachment for sewing machines comprising a pair of opposed semi-cylindrical members for engagement on a shaft, means for holding said members fixedly on said shaft, foundation strips mounted on said members and flexible fan blades mounted on said strips and projecting substantially radially of said shaft, each of said members having flanges opposed to each other, and bolts through said flanges for holding the members on said shaft, fan blades secured between the said flanges by the last said bolts, the said fan blades being covered by a soft covering material.

9. A fan attachment for sewing machines comprising a pair of opposed semicylindrical members for engagement on a shaft, bolts engageable through adjacent portions of said members for holding them fixedly on said shaft, and a fan blade engaged in between said members and held

by said bolts, said fan blade comprising a rigid core and a soft covering member thereon, said covering member being cut out to expose a portion of the core through which said bolts pass.

PAUL PARKOFF.
